UNITED STATES PATENT OFFICE.

JOHN LEWIS, OF ELIZABETH, NEW JERSEY.

IMPROVED RUDDER.

Specification forming part of Letters Patent No. 42,494, dated April 26, 1864.

To all whom it may concern:

Be it known that I, JOHN LEWIS, of Elizabeth, in the county of Essex and State of New Jersey, have invented, made, and applied to use a certain new and useful Improvement in Rudders; and I do hereby declare the following to be a full, clear, and exact description of my said invention, reference being had to the annexed drawings, making part of this specification, wherein—

Figure 1 is a plan of said rudder. Fig. 2 is a side elevation of the same and Fig. 3 is a view of the front edge of the rudder.

Similar marks of reference denote the same parts.

The nature of my said invention consists in wings or auxiliary rudders attached to the main rudder on each side thereof, whereby the rudder does not have to be as broad as now usual, and there is less liability of its being broken and less power is required at the helm. I apply said wings in such a manner that one wing will close against the rudder by the action of the water on the side toward which the rudder is moved, while the opposite wing acts to balance the action by the water on the rudder, thereby relieving the helm from strain.

In the drawings, *a* is the rudder, of any usual size or shape, and attached to the stern-post *c* by any convenient means, and the rudder-stock *b* extends up into the vessel and is actuated by any suitable helm or steering apparatus.

d d are my wings or blades, sustained by arms or braces, *e e*, extending from the sides of the rudder. These arms are inclined forward, (see Fig. 1,) and the wings at their ends are, when the rudder is straight in advance of the rudder, in order that the surfaces exposed to the action of the water may be nearly equal all around the vertical axis or center of motion of the rudder, so that the rudder may be held more easily in consequence of the action of the water being thus balanced. The wing, being in advance of the rudder, also prevents said wing acting in the eddy water. In Fig. 1 it will be seen that the front edge of said wing stands nearly opposite the rudder-post for the purpose aforesaid, although the rudder is in a diagonal position.

The arms or braces *e e* might be rigid. I, however, prefer to have them formed as joints

at both ends, so that the wing can swing with the moving ends of said arms and come against the side of the rudder. Chains *f f* may be attached to these wings and pass up through or on the outside of the rudder-stock, by drawing on which the wings will be brought up against the sides of the rudder for the safety of those wings while lying in port or in case of drift ice, &c.

The ends of the braces or arms *e e* next the rudder may be attached by any suitable joints; but to facilitate repairs to the wings I prefer that such joints be formed by rings, eyes, or hooks at the ends of chains or ropes passing up through tubes or grooves in the rudder, as represented by dotted lines at *g*, and the lower ends of such holes or grooves determine the point at which the rings stop and on which the arms swing; or said chains may pass beneath cross-pieces or hooks, or through the rudder and up on the opposite side, and thereby retain the ends of the arms in position against the rudder. The arms themselves should be formed so as to present their narrowest edge to the passing water, and may be braced for strengthening them, and said arms may be provided with slots to pass over hooks attached to the rudder, as at *i*, for forming an additional attachment for such arms.

It will be seen that the blade on the forward side of the rudder, when turned diagonally, will be closed down against the rudder itself by the action of the water on its outer side, and that the other blade, by the action of the water against its inner side, will be moved out from the rudder, and tend to turn the rudder itself into a still more diagonal position, thus relieving the helm of strain to a considerable extent and at the same time acting in such a way as to turn the ship in the proper direction. The wings, when applied to a rudder behind a propeller, are to be of such a shape that they cannot come in contact with the propeller-blades, and they may swing either downward or upward in closing, and, if desired, with wings folding upward against the rudder, chains attached from the vessel to the upper end of the wings may sustain their weight when in a normal position. I have shown by red lines, Fig. 3, ropes from the upper ends of the wings crossed, and they are to extend upward and backward to the overhanging stem of the vessel, so as to close

the wing that is on the side toward which the rudder is moved. Ropes may be substituted for chains, and rods may be introduced in connection with the chains in some portion of their length.

It will be evident that two wings on each side might be used in place of one, and that the ropes or chains *f* should lead to a device near the helmsman that can be operated by his foot, so as to slacken up those chains and allow the wings to open or draw in those chains to close the wings against the sides of the rudder. Recesses may be made for such wings in the rudder, and a spring beneath each may be employed to move the wings out from such recess when the ropes *f* are slackened. The wings may be fitted to open farther from the rudder at the bottom than at the top if the upper arms are the shortest. If it is desired to move the wings out from the rudder without their being elevated or depressed, as required for shallow water, the arms *e e* may be attached to the rudder on vertical hinges, so as to swing out horizontally and carry with their outer ends said wings, which

wings will swing open in this direction by the action of the water so soon as the rudder is moved diagonally to the vessel's length. It will be evident that when the wings are placed slightly forward of the rudder, the steering will be much easier; but these wings might be opposite or to the rear of the rudder, if required for the particular vessel.

What I claim, and desire to secure by Letters Patent, is—

1. Wings on each side of the rudder acting substantially in the manner and for the purposes specified.
2. Wings attached by hinged or jointed arms for the purposes specified.
3. Attaching the arms of the wings to the rudder by the chains or ropes for the purposes specified.

In witness whereof I have hereunto set my signature this 5th day of March, A. D. 1864.

JOHN LEWIS.
